OVERALL BUCKLE

Filed July 2, 1934

UNITED STATES PATENT OFFICE

1,993,691

OVERALL BUCKLE

Fred Summers, St. Joseph, Mo.

Application July 2, 1934, Serial No. 733,428

5 Claims. (Cl. 24—73)

This invention relates to improvements in buckles and has for its object to provide a buckle which may be formed from a single piece of wire, or stamped from a single piece of sheet metal.

Another object of the invention is to provide a buckle for overalls or the like so formed that it may easily be removed for laundering purposes.

Another object of the invention is to provide a buckle for overalls or the like so formed that it may be used at either the upper end or the lower end of a suspender strap.

A still further object of the invention is to provide a suspender buckle formed of wire and having a series of friction bars for holding the same from slipping on the webbing.

To the above ends essentially, and to others which may hereinafter appear, the invention consists of such parts and such combination of parts which fall within the scope of the invention as claimed.

In the drawing:—

Figure 1 is a side elevation of the buckle;

Figure 2 is a view similar to Figure 1 looking towards the opposite side of the buckle;

Figure 3 is a section on line 3—3 of Figure 1;

Figure 4 is an elevational view illustrating one manner of applying the buckle to a strap;

Figure 5 is a similar view showing another manner of its application;

Figure 6 is a view similar to Figure 1, of a modification; and

Figure 7 is a perspective view of another modification.

Like reference characters indicate corresponding parts throughout the several views of the drawing. The buckle shown in Figures 1 to 5 is indicated at 1 and is formed of a single piece of wire 2, the formation of which will now be traced starting at that terminal of the wire formed into

an eye 3 from which a bar 4 extends. This bar is provided with a series of anti-slipping crimps 5. The end 6 of said bar merges into an upstanding right angularly disposed part forming a spacer portion 7, which is bent at 8 and turned in parallel

45 with bar 4, and stops short of the outer end of said bar, and is then returned out upon itself, to form a finger 9, the end portion 10 of which terminates about on a plane with the member 7. From the point 10 the wire is then upwardly and

50 inwardly inclined to form neck portion 11, and coiled upon itself to form a one coil spring 12 from which spring the wire is shaped to form a button receiving loop 13. At the terminal 14 of this loop the wire is again coiled upon itself to

55 form the one-coil spring 15. From the spring 15

the wire is carried downwardly and outwardly to a bend 16, from whence it is bent to form another inturned finger 17, similar to finger 9. From the terminal 18 of said finger the wire is bent down at right angles to form a bar 19 which runs through the eye 3, which eye is maintained at about the center of member 19. At the lower end 20 of bar 19 the wire is again bent at right angles to form another crimped bar 21, paralleling bar 4. The end 22 of bar 21 is bent up at right angles to form an extension 23 of the side bar 7. The terminal 24 of the extension 23, such terminal being the other terminal of the wire, is bent around the end 10 of bar 4, which completes the structure.

To use the buckle, (see Fig. 4) the end 25 of a suspender strap 26, is bent upon itself to form a loop 27, which loop is first projected between bars 21 and 4, then the loop is doubled upon itself to permit the fingers 9 and 17 to enter between the heels 28 and 29 thereof, whereupon the buckle is ready for use. The crimped bars between which the strap end passes, will frictionally hold said strap folded over the fingers 9 and 17 and prevent any slipping. However, to adjust the buckle is a very simple matter, it being only necessary to draw the strap toward the button loop 13 and pull one end or the other strap down or away from loop 13.

The strap end 25 may also be fixed to the buckle in the manner illustrated in Figure 5, in which case the strap is threaded between bars 4 and 21, under the latter and over the former; thus the hold of the strap onto the buckle is secure.

It is obvious that the above described buckle may be used just as effectively on the lower ends of a suspender strap as on the upper ends of a bib strap.

The springs 12 and 15 make the neck 11 give to permit the entrance of a button shank into loop 13, and then spring back to normal position whereby said shank cannot accidentally pass there-between from said neck.

In Figure 6 I show a modification of the invention in which the buckle 30 is stamped from a single piece of sheet metal, the fingers 31 and 32, in this case, being solid, the bars being crimped in the stamping process. The neck portion between 35 and 36 will flex sufficiently upon pressure of the fingers in opposite direction thereon to permit entrance of the button shank into the button loop 37.

In Figure 7 I show a modification of the invention in which 38 indicates a buckle formed of

two pieces of wire 39 and 40 only, the piece 39 being in all respects similar to the buckle of Figure 1 except that its lower loop 41 has its side arms 42 and 43 extended to form a wider loop in order to permit the addition of the extra transverse bar 40 intermediate and parallel with the bars 44 and 45. All three of bars 40, 44 and 45 are crimped to provide friction. This form of the invention is especially adaptable for use on suspenders used by brick layers, masons and others who do a lot of stooping and require an especially strong gripping buckle.

Having now described my invention, that which I claim to be new, and desire to procure by Letters Patent is:

1. A buckle having a pair of parallel bars and a pair of inwardly projecting fingers for entering between the folds of a strap projected between said bars, said bars and fingers being in a common plane, said buckle having a button receiving loop, said bars being crimped, said buckle being formed of wire, the terminals of which are carried upon one of said bars.

2. The device as claimed in claim 1, said loop having a reduced neck.

3. The device as claimed in claim 1, said loop

having a reduced neck, said wire having coils at said neck.

4. A buckle having a pair of vertical side portions, a plurality of spaced parallel horizontal bars connected to said side portions, a pair of inwardly extending oppositely disposed fingers positioned in spaced relation to the upper of said bars and connected to said side portions, an upstanding resilient button receiving loop open at one end and closed at its other end, said loop gradually increasing in width from its open to its closed end, connection means between the open end of said loop and said fingers, the sides of the button receiving loop adjacent its open end being formed with a pair of spring coils, and with the connection means between the fingers and loop merging into said spring coils.

5. A buckle of the construction set forth in claim 4 wherein said side portions, loop, bars and connection means are formed from a single length of wire having one of its terminals encompassing one of said side portions and the other of its terminals encompassing one of said bars.

FRED SUMMERS. 25
